(No Model.)

W. PLOWRIGHT.
BAND CUTTER AND FEEDER.

No. 423,629.

Patented Mar. 18, 1890.

UNITED STATES PATENT OFFICE.

WILLIAM PLOWRIGHT, OF BLANDINSVILLE, ILLINOIS.

BAND-CUTTER AND FEEDER.

SPECIFICATION forming part of Letters Patent No. 423,629, dated March 18, 1890.

Application filed November 9, 1889. Serial No. 329,744. (No model.)

To all whom it may concern:

Be it known that I, WILLIAM PLOWRIGHT, a citizen of the United States, residing at Blandinsville, in the county of McDonough 5 and State of Illinois, have invented a new and useful Band-Cutter and Feeder, of which the following is a specification.

My invention relates to improvements in band-cutters and feeders; and it consists in 10 certain novel features hereinafter described and claimed.

In the drawings, Figure 1 is a perspective view of my improved band-cutter and feeder. Fig. 2 is a longitudinal section of the same, 15 and Fig. 3 is a transverse section. Fig. 4 is a top plan view.

Referring to the drawings by letter, A designates a supporting-frame, in which I arrange the endless carrying-aprons B B, and between 20 the said aprons I arrange the plates C, having the longitudinal slots D, as clearly shown. A rotary knife E is arranged between the plates C, and consists of a shaft F and a series of knives G, secured to the said shaft and projecting radially therefrom and adapted to pass 25 through the slots D. The shaft F is journaled in the supporting-frame, and one end of the same is extended beyond the side of the frame and provided with a band-pulley H. A belt 30 or band I passes around this pulley H and a similar pulley J on the end of the shaft of the upper apron B, and thereby transmits motion to the said apron. The lower apron receives 35 its motion directly from the driving-wheel of the thrashing-machine, and a belt K extends from the roller of the said apron to the pulley H, so as to impart motion to the rotary knife.

On the upper side of the supporting-frame, near the lower end of the same, I provide the 40 standards L, the upper ends of which are bifurcated and provided with a series of transverse perforations M. Journal-boxes N are mounted in the bifurcations and are held at any desired point of the same by pins O, inserted through the said perforations above and 45 below the said boxes. An endwise-movable shaft or rod P is mounted in the boxes N and has a series of teeth Q depending from its lower side, as shown. The said rod is further 50 provided with an upwardly-projecting pin R, and a pitman S has one end pivoted on the

said pin and its other end pivoted on a crank-arm T at the upper end of a rotary shaft U, which is mounted in suitable bearings on the side of the frame. This shaft U is composed 55 of two telescoping members V W, and is provided at its lower end with a pulley X, which receives motion from the roller of the upper apron through a belt or band Y.

Having thus described my invention, what 60 I claim, and desire to secure by Letters Patent, is—

1. The combination, with the frame and the endless aprons arranged therein in alignment with each other, of the slotted plate between 65 said aprons, the rotating shaft journaled across said plate, and the radial blades carried thereby and playing through the slots in the plate, substantially as described.

2. The combination, with the frame, the 70 aprons therein, and the standards L at the sides of the frame, said standards having bifurcated upper ends forming arms provided with perforations M, of the bearings N, adjustable vertically between said arms, pins O, 75 passing through said perforations above and below the bearings, the rod P, sliding longitudinally in said bearings and having teeth A, and means, substantially as described, for imparting a longitudinal reciprocation to said 80 rod, as and for the purpose set forth.

3. The combination, with the frame, the 85 aprons therein, and the standards L at the sides of the frame, said standards having bifurcated upper ends forming arms provided with perforations M, of the bearings N, adjustable vertically between said arms, pins O, 90 passing through said perforations above and below the bearings, the rod P, sliding longitudinally in said bearings and having teeth A and upwardly-projecting pin R, the telescopic rotating shaft U, journaled in the side 95 of the frame, the crank T at the upper end thereof, and pitman S, connecting said crank and pin, as and for the purpose set forth.

In testimony that I claim the foregoing as my own I have hereto affixed my signature in presence of two witnesses.

WILLIAM PLOWRIGHT.

Witnesses:

MARIEN CUFFMAN,
Wm. BLACKHURST.
